UNITED STATES PATENT OFFICE.

CHESTER B. MILLS, OF EAST MCKEESPORT, PENNSYLVANIA, ASSIGNOR TO WESTINGHOUSE ELECTRIC & MANUFACTURING COMPANY, A CORPORATION OF PENNSYLVANIA.

STRUCTURAL-STEEL FRAME FOR DYNAMO-ELECTRIC MACHINES.

Application filed November 16, 1918. Serial No. 282,895.

To all whom it may concern:

Be it known that I, CHESTER B. MILLS, a citizen of the United States, and a resident of East McKeesport, in the county of Allegheny and State of Pennsylvania, have invented a new and useful Improvement in Structural-Steel Frames for Dynamo-Electric Machines, of which the following is a specification.

10 My invention relates to dynamo-electric machine frames and it has particular relation to the frames of relatively large machines and supports therefor, having for its object the provision of a novel, rugged, 15 simple and inexpensive structure of the character designated.

Heretofore, it has been customary, especially in large machines of the above-mentioned character to cast the feet integral 20 with the frames. This practice is objectionable because a defective foot portion of a casting may necessitate condemnation of the entire casting and also because castings of large size are more likely to have defects 25 than those of relatively small size. Furthermore, when a machine is to be mounted in a very limited space, such, for example, as in a ship hull, it is sometimes desirable 30 to mount the supports thereof at different levels, which, of course, requires special drawings, special patterns and special castings, the expense of which is very great for large machines.

By my invention, I provide a foot member 35 separate from the frame, which may be mounted thereon in any position so that, for a special machine, all parts will be standard except the foot casting which is relatively simple and inexpensive. Also, the foot is so 40 constructed that the frame is strengthened thereby, which is very desirable, especially in built-up skeleton frames which are now coming into more general use. Such a structure also has the additional advantage that 45 it is not necessary to know the exact mounting facilities before the building of the machine may be started, as is necessary when a cast-on support is used.

By my invention, I provide also a novel 50 method of forming a frame of the character designated and novel means for attaching together component parts of such frame.

Referring to the accompanying drawings, Fig. 1 is an end elevational view of a por-

tion of a dynamo-electric machine frame 55 constructed in accordance with my invention; and Fig. 2 is a view of the structure shown in Fig. 1, partially in section and partially in elevation, the section being taken along the line II—II of Fig. 1.

The frame of my machine consists of a plurality of annular members 1 of substantially channel shape in cross section and held in side-by-side spaced relationship by means of cover plates 2 and 3 upon the outer periphery thereof and by bars 4 that extend at right angles to said annular members and are riveted to the inner peripheries thereof. Each of the annular members 1 consists of two semi-annular members 5 and 6 which are joined together by means of bolts 7 and the flanges of clamping members 8 which are riveted to ring sections 5 and 6 and also by means of bolts 9 and flanges 10 of bars 11 and 12 which are 75 riveted to the inner peripheries of the members 5 and 6, respectively. The bars 4 serve also as a means for mounting laminations 13 within the frame. The frame is provided with two supporting members 14 and 15, 80 each comprising an arcuate portion 16 of substantially the same radius of curvature as the outer periphery of the members 1, and a foot portion 17 by which it is attached to a suitable base. Each of the supporting members 14 and 15 is of substantially 85 the same width as the entire machine and the arcuate portion 16 thereof is attached to each of said annular members 1 by means of rivets 18.

The members 5 and 6 are formed by rolling or pressing standard structural-steel forms, such as channel or I-bars into semi-annular members which are afterwards fastened together as previously described. By 95 reason of the fact that the periphery of the rings 1 is substantially covered by the clamping members 8, supports 14 and 15 and the arcuate plates 2 and 3, the structure is rendered very strong and rigid with a 100 minimum amount of weight.

From the foregoing description, it will be understood by those skilled in the art that, in building a special machine, irrespective of the fact that the mounting 105 facilities therefor are unknown, the building operation may be started, since the only special parts necessary are the supporting

members which may be mounted anywhere upon the periphery of the machine frame.

While I have shown but one form of my invention, it will be obvious to those skilled in the art that it is not so limited but is susceptible of various minor changes and modifications without departing from the spirit thereof, and I desire, therefore, that only such limitations shall be placed thereupon as are imposed by the prior art or are specifically set forth in the appended claims.

I claim as my invention:

1. In a dynamo-electric machine, a frame comprising a plurality of annular members mounted in side-by-side relation and each comprising two semi-annular sections adapted to be detachably secured together, bars

attached to the inner periphery of each of said annular members, and means joining the bars at adjacent ends of two sections.

2. In a dynamo-electric machine, a frame comprising a plurality of annular members mounted in side-by-side relation and each comprising two semi-annular sections, bars attached to each of said annular members and flanges provided on the bars at the ends of the sections, and means for attaching together the flanges of coacting bars on the two sections.

In testimony whereof I have hereunto subscribed my name this 28th day of Oct., 1918.

CHESTER B. MILLS.
